UNITED STATES PATENT OFFICE.

ANDREW SHEARER, OF FRANKFORT, KANSAS.

LISTER-PLOW.

1,286,127.

Specification of Letters Patent. Patented Nov. 26, 1918.

Application filed December 21, 1917. Serial No. 208,268.

To all whom it may concern:

Be it known that I, ANDREW SHEARER, a citizen of the United States, and a resident of Frankfort, in the county of Marshall, 5 State of Kansas, have invented certain new and useful Improvements in Lister-Plows, of which the following is a specification, reference being had to the accompanying drawings.

10 This invention relates to improvements in lister-plows and has for one of its objects the provision of means for enabling the plow-body and the frame to which it is attached to be moved, at the completion of each fur- 15 row, from one side of the machine to the other. Such movement of the plow-body allows two important ends to be attained, which are, in the order of their importance, first, the "double listing" of the field, and 20 second, the plowing of the first and last furrows closer to the boundary fences of the field than would be possible where the plow body remains in a fixed central position relative to the supporting wheels. By "double 25 listing" is meant bursting out previously formed ridges between successive furrows, spaced the usual distance apart, and forming in place of such ridges additional furrows for the reception of seed. Such double 30 listing is becoming increasingly popular as its advantages are recognized. Such advantages are that the ground is of course more thoroughly plowed; it is put in better shape for cultivating; it absorbs excessive rains 35 better; the deposited seed is not so liable to be washed out, and the roots of the plants are given a better chance to extend themselves—all of which results in a larger yield. While the above-recited advantages of 40 double listing are quite generally recognized, it is frequently not resorted to owing to the difficulty of properly accomplishing it with the ordinary lister-plow, for in doing it with an ordinary lister-plow—that is, one where 45 the plow-body remains at substantially the longitudinal center of the machine—much depends upon the skill of the operator in driving his horses and also upon the correct walking of the horses. Indeed, the utmost 50 care is constantly required to prevent the plow from being deflected to one side of the center of the ridge and into one of the adjacent previously-formed furrows.

By my improved construction wherein the 55 plow-body is maintained at one side or the other of the machine the difficulty of main-

taining the plow-body centrally of the ridge is obviated. To so maintain it I space the supporting wheels a distance apart substantially equal to one and one-half the distance 60 between the rows that are formed for single listing (instead of twice the distance between such rows as is commonly done with wide-tread listers) and, therefore, am always enabled to utilize previously-formed 65 furrows as guides or gages for keeping the plow-body properly positioned with respect to the ridge that it is working upon. One of such guiding or gaging furrows for the 70 double-listing operation is a furrow previously made in single listing while the other one will be a furrow made in the double-listing.

When the machine is used for single listing it is necessary, of course, at the end of 75 each furrow to level up the machine by depressing the wheel-frame at one side of the machine and correspondingly raising the frame at the opposite side, for, of course, the wheels alternately run in a furrow and 80 on the unplowed ground. It is one of the objects of the invention to provide improved leveling means which can be either manually operated by the driver from his seat or be automatically operated (which latter I 85 consider preferable) by the shifting of the plow-body from one side of the machine to the other. These stated leading objects of the invention I accomplish by the devices and combinations of devices illustrated in 90 the drawings and hereinafter particularly described. That which I believe to be new will be pointed out in the claims.

In the drawings,—

Figure 1 is a plan view of a machine embodying my improvements with the plow-body and its laterally-adjustable supporting frame shifted to the right-hand side of the machine;

Fig. 2 is a side elevation of the machine 100 of Fig. 1;

Fig. 3 is a detail being a view in rear elevation of the wheel-frame and some of the parts connected therewith and showing the plow supporting frame shifted to the right-hand side of the machine, the parallel longitudinally-extending members of such frame being in section;

Fig. 4 is a view similar to Fig. 3, but with the plow supporting frame shown as shifted 110 to the left-hand side of the machine;

Fig. 5 is a detail being an enlarged view

in perspective of a portion of the wheel-frame and shiftable plow supporting means;

Figs. 6 and 7 are diagrammatic views showing, respectively, the results of single 5 and double listing, and the relative arrangement of the plow-body and the supporting wheels of the machine;

Fig. 8 is a view very similar to that shown in Fig. 4, but illustrating a modified construction whereby the wheel-frame is automatically adjusted as the plow-body and its 10 supporting frame are laterally shifted; and

Fig. 9 is a vertical section taken at line 9—9 of Fig. 8.

15 Referring to the drawings in which corresponding parts are indicated by like reference numerals—10 indicates a double mold-board lister plow-body, and 11 the beam therefor, which beam is mounted in the usual 20 manner upon a crank shaft 12 the ends of which are journaled in suitable brackets 13 secured to the side members of a plow-supporting frame 14, which frame is supported at its rear end by a pair of caster wheels 15

25 and near its front end by side wheels 16,—the particular means of connecting the frame 14 with the side wheel members being hereinafter set forth. On one of the side members of the frame 14 is secured a 30 segmental rack 17 with which co-operates a hand lever 18 rigidly connected to the crank shaft 12 whereby the plow is raised or lowered as desired relative to the frame 14, and is held in its adjusted position by the engagement of

35 an ordinary spring latch on the lever with one of the notches of the rack. In rear of the plow-body is shown a seed hopper 19 supported by inclined disks 20, the rotation of which operates seed-dropping mechanism

40 at the bottom of the hopper, as usual, so as to cause a discharge of seed through the inclined spout 21. The supporting wheels 16 are each supported on axle members or spindles 22 that extend outward from the 45 lower ends of two vertically-disposed standards 23. Against the inner face of each of these standards 23 is arranged a bar 24, these two bars being connected together by upper and lower cross-bars 25 and 26, re-

50 spectively, which as shown are preferably made of pipe sections. These vertical bars 24 and cross-bars 25 and 26 form a frame, which, together with the standards 23 that carry the supporting wheels, may be con-

55 sidered as a wheel frame. Each standard 23 is connected to its adjacent vertical bar 24 by clips 27 which are made fast to the bars 24 and embrace the standards in such manner that the bars 24 can be moved vertically

60 relative to the wheel standards. The two cross-bars 25—26 are braced together at their central portions by braces 28 bolted to them, said braces in turn being secured together by a bolt 29 (see Fig. 5). The supporting 65 frame 14 is connected to the wheel frame

and supporting frame by means of an arch member formed of a front and rear section 30—31, respectively, said sections being spaced apart a sufficient distance to accommodate between them the cross-bars 25—26 70 of the wheel frame. The horizontal portions of these arch sections are connected together by suitable bolts 32 and their vertical portions are secured together above and below the lower cross-bar 26 by bolts or rivets, 75 upon which bolts or rivets are rotatably mounted rollers 33 that bear against the upper and lower sides of such cross-bar 26. 34 indicates two brackets affixed respectively to the central portions of the horizontal 80 members of the arch 30—31, in which brackets is journaled the forward end of a rod 35 that has suitably affixed to it between the said horizontal members of the arch a gear 36. This gear is in mesh with a rack 85 bar 37 that is secured in any suitable manner to the upper surface of the upper cross-bar 25. The rear end of the rod 35 passes through and is journaled in the rear end of a long bracket 38, which, as best shown in 90 Fig. 5, is here constructed of a single bar bent centrally and having its ends turned and bolted at opposite sides of the central portion of the rear member of the arch 30—31—being shown as secured by two of the 95 bolts 32 before referred to. 39 indicates an annular plate affixed in any suitable manner to the rear end of the bent bar or bracket 38, through which plate the rod 35 projects. The plate 38 has a rearwardly extending 100 flange in which, as clearly shown in Fig. 5, are formed a plurality of notches. 40 indicates a crank that is pivotally attached to the rear projecting end of the rod 35 and by means of which the rod 35 is rotated. The 105 crank handle by reason of its pivotal connection with the rod is adapted to be pushed forward, as shown in Fig. 2, so as to engage with one of the notches in the plate 39 and thereby lock the rod against further rotation. 41 indicates two diagonal braces bolted at their upper ends to the forward member 30 of the arch and at their lower ends to the respective side bars of the 110 frame 14.

As clearly shown, the lower ends of the vertical legs of the double arch 30—31 are bolted to the frame 14 near the forward end thereof, and, therefore, constitute in effect a part of the plow-supporting frame 14. With 120 the plow-body raised out of the ground it is evident that such plow-body and its supporting frame, comprising the members 14 and 30—31, together with the parts attached to those members, can be shifted laterally 125 of the wheel frame as may be desired, this being accomplished by the operator from his seat rotating the shaft 35 by means of the crank handle 40. Such rotation causes, of course, a rotation of the gear 36 affixed to 130

the forward end of the shaft, and as it is in constant engagement with the rack-bar 37, the arch 30—31 and the parts secured thereto are necessarily moved laterally of the machine. When moved to the extent desired, the arch is to be locked in that position by the driver causing an engagement of the crank handle with one of the notches in the flanged plate 39.

10 Where trenches or furrows are to be formed as in ordinary listing—known as “single listing”—one of the supporting wheels 16 runs in the last trench or furrow that has been made while the other of such 15 wheels runs upon the unplowed and consequently higher ground, and hence it becomes necessary at the beginning of each furrow to level the machine by suitably raising that wheel which had before run 20 in a furrow and correspondingly lowering the other wheel which is now to run in the last made furrow, but which had previously ran on the unplowed ground. To accomplish this leveling operation, I provide two 25 parallel cross-bars 42 each centrally pivoted upon one of the braces 28 that connects the two bars 25 and 26 together. These cross-bars 42 are shown as pivoted against the outer faces of these two braces 28, the bolt 30 29, heretofore referred to, constituting the pivot. The ends of these cross-bars 42 are connected to the two wheel standards 23 so that as such cross-bars are rocked upon their pivot they will, relatively, raise one 35 such wheel standard and its wheel and correspondingly lower the other wheel standard and wheel. As shown in the drawings, the connection between the cross-bars 42 and each wheel standard is made by reducing 40 the ends of such cross-bars and projecting them through the end portions of short strips 43 that are secured to the outer faces and near the upper end of said wheel standards. Any other appropriate manner of 45 securing the cross-bars to the wheel standards could, of course, be employed. To the outer face of one of the vertical bars 24 and close to its upper end is rigidly secured a toothed segment 44 that projects rearwardly.

50 Pivoted alongside of this segment is a lever 45 provided with an ordinary spring latch for engaging the teeth of the segment, such lever being preferably slightly inclined toward the center of the machine to be more 55 conveniently in reach of the driver. To this lever, forward of its point of pivotal attachment to the segment, is pivotally attached the upper end of a short link 46, the lower end of which is pivoted to the 60 central portion of the outer face of that short strip 43 at that side of the machine. It is evident that by a movement of the lever 45 that one of the bars 24 that is connected to the lever by means of the rack 65 44 will be moved either up or down accord-

ing to the direction of movement of the lever, and this will, of course, cause a relative reverse movement of the adjacent standard 23 and also a turning of the cross-bars 42 on their central pivot and impart a corresponding relative movement in the reverse direction, to the other wheel standard with which said cross-bars are connected. A single movement of the lever, therefore, raises one side of the wheel-frame and lowers the 70 other side to the same extent, and hence, the desired leveling of the machine can be quickly accomplished.

In practising single listing, some farmers desire the width between furrows to be a 80 little greater than others, and accordingly the supporting wheels 16 are preferably made laterally adjustable on their respective spindles and when adjusted as desired fixed in place in any usual manner; such 85 differences in width can also be accomplished by the extent to which the plow and its supporting framework are shifted laterally, and it is because of the fact that it may not always be shifted to the extreme 90 extent to one side or the other that I provide the flange of the annular plate 39 with a plurality of notches which enables the handle to be locked in place as described regardless of the radial position that the 95 handle is in when the locking of the parts is to be effected. During all of the plowing operations, however, it is the intention when using my improved machine to have the plow-body located well toward one side of 100 the machine, whereby the furrow being formed will be at the desired distance from the previously formed furrow in which one of the supporting wheels is traveling, as is clearly illustrated by Fig. 6. Upon the 105 completion of the furrow, the machine is, of course, turned around preparatory to making the next furrow, and the wheel that had been running upon the unplowed ground is directed into the last-named furrow to serve as a guide. It is then, of 110 course, necessary that the plow-body be shifted toward the opposite side of the machine so that it occupies the same position relative to the wheel at that side that it 115 had previously occupied with respect to the other wheel. When so shifted, and the leveling operation having been performed as described, the furrow then to be made will be properly spaced from the previous 120 furrow. It is with especial reference, however, to “double listing” that the shifting of the plow-body from side to side for the formation of successive furrows applies. As before stated, the furrows or trenches 125 formed in the practice of “double listing” are formed between the single listing furrows or trenches and the spaces where these double listing furrows must be formed are difficult to accurately plow owing to the 130

quantity of dirt that has been thrown in ridges by the formation of the single listing trenches. By making the wheel frame of my machine approximately one and one-half times as wide as the distance between single listing furrows or trenches, I am able to run both of the supporting wheels 16 in trenches, as indicated clearly in Fig. 7, and by so doing I obtain by the two trenches 10 that the wheels run in a perfect guide for the forward progress of the machine, and those two trenches that the wheels run in also act to counteract any tendency of the plow-body to run out of a straight line,— 15 to wit, out of the center of the ridged space before mentioned. In the view shown in Fig. 7, the trenches indicated by *a* are those formed in the process of single listing while those indicated by *b* are those formed in the 20 process of double listing, and it will be noted that one of the supporting wheels runs in one of the trenches *a* while the other runs in one of the trenches *b*. This must always be so after the formation of 25 the first double listing trench or furrow, and this very valuable feature of providing a guiding and retaining trench for each wheel to run in during the making of a trench in the ridged space between two single listing trenches is made possible not 30 only by reason of the lateral shifting of the plow-body for the formation of successive trenches, but also by reason of the formation of the wheel frame of a width 35 that the wheels thereof are spaced apart approximately one and one-half the distance between adjacent trenches made in the single listing. The width of the wheel frame, therefore, bears a very distinct relation 40 to the work to be performed as it permits the carrying wheels to run in the trenches designated as *a* and *b* and also permits the plow-body to be adjusted with proper relation to the ridged space between 45 two of such furrows or trenches that are indicated by *a*.

With the machine employed in double listing there will be no occasion, of course, for leveling the machine at the completion 50 of each furrow or trench because both of the wheels will travel on the same level, and, therefore, the adjusting lever 45 will be moved to a proper position to hold the leveling cross-bars 42 horizontally.

55 In single listing it is necessary, as hereinbefore pointed out, to level the machine at the completion of each furrow in order that the wheel which had run in a furrow should, during the next traverse of the field, run on 60 the higher unplowed ground, and vice versa, and while I have shown in Figs. 1, 2, 3 and 4 a very simple and effective means for manually accomplishing such leveling, the operation is capable of being, and prefer-

ably, performed automatically upon the lateral shifting of the plow-body and its supporting frame, and such automatic means is illustrated in Figs. 8 and 9, to which reference is now made. In these figures, showing the modification, the parts that correspond in construction to those heretofore described are indicated by the same reference numerals with the addition of the letter *a*. In this construction the leveling cross-bars are not centrally pivoted in place 65 on a fixed pivot as in the other construction, but the rear one has pivoted to it at 47 two bars 48, the pivot 47 for each bar being substantially midway between the ends 70 of the bar. The bars 48 at their inner ends 75 are pivoted together by a pin 49 and from this pivot pin 49 depends a link 50, the turned lower end of which is engaged by the short end of a hand lever 51 that is pivoted at 52 to a segmental toothed segment 53, bolted to and projecting rearwardly from the rear brace 28^a that extends 80 between the two cylindrical cross-bars 25^a and 26^a. The lever 51 is provided with the usual spring latch for engaging the segment and it is evident that by the use of the lever the bars 48 can be turned on their pivots 47 to any required position. On the rear face of each depending leg of the double arch member 31^a is journaled a roller 54. 85 Each of these rollers is so positioned with respect to one of the bars 48 that as the arch 30^a—31^a is moved toward the side of the machine the roller will come in contact 90 with the lower edge of its adjacent bar 48 and force the same upward so that it turns 95 on its end pivot 49. This upward movement, of course, is transferred through the pivot 47 of that bar to the cross-bar 42^a 100 causing the adjacent end of such bar 42^a 105 to rise. The other end is correspondingly lowered, and, as the ends of this cross-bar 42^a are connected, as above described, with the wheel standards, it is evident that one 110 wheel is relatively lowered to the same extent as the other one is raised. It is evident that automatic leveling will be effected in the manner described at each lateral shifting of the plow-body and its supporting frame, one roller 54 contacting one of 115 the bars 48 when the plow is moved toward one side while the other roller 54 causes a movement by contact with the other bar 48 when the plow and its frame are shifted to the other side of the machine. Of course, in 120 double listing no leveling movement will be required, and, therefore, through the lever 51 the inner ends of the bars 48 are pulled down to bring such bars into alignment with each other and parallel with the cross-bar 125 42^a which latter will itself assume a substantially horizontal position and thus level the wheel-frame. The two bars 48 are per-

mitted to be brought into alinement by reason of the fact that the openings through which the pivots 47 pass are in the form of slots, as indicated at 55.

5 What I claim as my invention and desire to secure by Letters Patent, is—

1. In a plow, the combination with a wheel-frame and furrow-forming means connected therewith, adapted to be moved

10 into and secured in operative position near one side of the wheel-frame for forming alternate furrows of a series of parallel furrows and to be moved into and secured in operative position near the opposite side of

15 such frame for forming the other furrows of said series, of means for moving such plowing means into and out of said two operative positions, the distance between the wheels of said wheel-frame being approxi-

20 mately one and one-half times the distance between adjacent furrows of the series, whereby upon the making of a second series of furrows between the furrows of said first series, and with the furrow-forming means

25 operatively arranged first at one side of the machine and then at the other, the wheels will respectively travel in and be guided by furrows of each series.

2. In a plow, the combination with a 30 wheel-frame and a plow-body connected therewith adapted to be secured in operative position near one side of the wheel-frame for forming alternate furrows of a series of parallel furrows and to be secured

35 near the opposite side of such frame for forming the other furrows of said series, of means for shifting said plow-body from one of said positions to the other, the distance between the wheels of said wheel-

40 frame being approximately one and one-half times the distance between adjacent furrows of the series, whereby upon the making of a second series of furrows between the furrows of said first series and with the

45 plow-body arranged and shifted as described the wheels will respectively travel in and be guided by furrows of each series.

3. In a plow, the combination with a 50 wheel-frame and a plow-body, of means for securing said plow-body to said frame with the plow-body positioned substantially midway between the longitudinal center of the frame and one of the wheels of the frame for forming alternate furrows of a series of

55 parallel furrows as the machine is moved in one direction across a field and for securing the plow-body in a corresponding position relative to the other wheel for forming the other furrows of the series as

60 the machine is moved in the opposite direction across the field, the distance between the wheels of said wheel-frame being approximately one and one-half times the distance between adjacent furrows of the series,

whereby upon the making of a second series 65 of furrows between the furrows of said first-named series and with the plow-body secured alternately toward opposite sides of the machine, as above described in connection with the first-named series, the 70 wheels will respectively travel in and be guided by furrows of each series.

4. In a plow, the combination of a wheel-frame, a plow-body connected therewith, means for shifting the plow-body laterally 75 into an operative position at either side of the longitudinal center of said wheel-frame, and means actuated by the shifting of the plow-body for raising one side and lowering the other side of the frame. 80

5. In a plow, the combination of a wheel-frame, a plow-body connected therewith, means for shifting the plow-body laterally into an operative position at either side of the longitudinal center of said wheel-frame, 85 means for locking it in either of its operative positions, and means actuated by the shifting of the plow-body for raising one side and lowering the other side of the frame. 90

6. In a plow, the combination of a wheel-frame, a plow-body connected therewith, means for shifting the plow-body laterally into an operative position at either side of the longitudinal center of said wheel-frame, 95 means movable with the plow-body for locking it in either of its said operative positions, and means actuated by the shifting of the plow-body for raising one side and lowering the other side of the frame. 100

7. In a plow, the combination with a wheel-frame, of a plow-body, means for connecting the same with said wheel-frame, said plow-body and connecting means both being shiftable toward either side of the 105 machine, and means actuated by the shifting of the plow-body for raising one side and lowering the other side of the frame.

8. In a plow, the combination with a wheel-frame, of a plow-body, means for 110 connecting the same with said wheel-frame, shifting mechanism carried by said connecting means for causing said plow-body and the connecting means to be moved toward either side of the machine, and means 115 actuated by the shifting of the plow-body for raising one side and lowering the other side of the frame.

9. In a plow, the combination with a wheel-frame, of a plow-body, means for connecting the same with said wheel-frame, shifting mechanism carried by said connecting means for causing said plow-body and the connecting means to be moved toward either side of the machine, means for locking said shiftable parts to the wheel-frame when in either of its said positions, and means actuated by the shifting of the plow- 125

body for raising one side and lowering the other side of the frame.

10. In a plow, the combination with a wheel-frame, of a plow-body, means for connecting the same with said wheel-frame, shifting mechanism carried by said connecting means for causing said plow-body and the connecting means to be moved toward either side of the machine, a locking device 10 carried by said connecting means for holding the same against lateral movement when in either of said positions, and means actuated by the shifting of the plow-body for raising one side and lowering the other side 15 of the frame.

11. In a plow, the combination with a wheel-frame comprising side bars and a cross-bar extending between them, of a plow-body, means movably mounted on said 20 cross-bar and connected with said plow-body so as to be movable laterally of the machine with the plow-body, other means for compelling a movement of said last-named means along said cross-bar to position the 25 plow-body at either side of the longitudinal center of the wheel-frame, and means actuated by the shifting of the plow-body for raising one side and lowering the other side of the frame.

30. 12. In a plow, the combination with a wheel-frame comprising side bars and a cross-bar extending between them, of a plow-body, means for movably connecting the plow-body with the wheel-frame, rack- 35 and-gear mechanism carried by said connecting means and the cross-bar, a shaft for turning said gear to cause a shifting of the plow-body from one side of the wheel-frame to the other, and means actuated by the 40 shifting of the plow-body for raising one side and lowering the other side of the frame.

13. In a plow, the combination with a wheel-frame comprising side bars and a cross-bar extending between them, of a plow-body, means for movably connecting the plow-body with the wheel-frame, rack- 45 and-gear mechanism carried by said connecting means and the cross-bar, a shaft for turning said gear to cause a shifting of the plow-body from one side of the wheel-frame to the other, means for locking the shaft against rotation to hold the said plow-body and said connecting means against lateral 50 movement, and means actuated by the shifting of the plow-body for raising one side and lowering the other side of the frame.

55. 14. In a plow, the combination with a wheel-frame comprising side bars and two cross-bars located one above the other and extending between the upper portions of said side bars, of a plow-body, a supporting member for said plow-body connected therewith and extending upward in proximity

to said two cross-bars, a rolling connection 65 between said member and one of said cross-bars, and a rack-and-gear connection between said member and the other of said cross-bars, and means for rotating the gear to cause a shifting of the plow-body from one 70 side of the wheel-frame to the other.

15. In a plow, the combination with a wheel-frame comprising side bars and a cross-bar extending between the upper portions of said side bars, of a plow-supporting 75 frame of materially less width than the wheel-frame, said plow-supporting frame comprising two horizontal side members between which a plow-body is located and to which it is connected and an upright arch 80 connected to said side members, said arch being movably mounted on the cross-bar of the wheel frame.

16. In a plow, the combination with a wheel-frame comprising side bars and a cross-bar extending between the upper portions of said side-bars, of a plow-supporting frame of materially less width than the wheel-frame, said plow-supporting frame comprising two horizontal side members between which a plow-body is located and to 90 which it is connected and an upright arch connected to said side members, said arch being movably mounted on the cross-bar of the wheel-frame, and means for moving said 95 plow-supporting frame laterally of the wheel-frame.

17. In a plow, the combination with a wheel-frame comprising side bars and two cross-bars extending between said side bars, 100 of a plow-supporting frame of materially less width than the wheel-frame and comprising two horizontal side members and an upright arch member, a plow-body connected with said plow-supporting frame, 105 means for movably supporting said upright arch member from one of the cross-bars of the wheel-frame, and means carried by said arch member for engaging the other one of the cross-bars to cause a lateral shifting of 110 the plow-supporting frame relative to the wheel-frame.

18. In a plow, the combination with a wheel-frame comprising side bars and two cross-bars extending between said side bars, 115 of a plow-supporting frame of materially less width than the wheel-frame and comprising two horizontal side members and an upright arch, said arch having two principal parts connected together and to the said 120 horizontal side members and arranged upon opposite sides of the said cross-bars of the wheel-frame, a rolling support secured between the two arch members and bearing upon one of the cross-bars of the frame, and 125 means carried by said arch and engaging the other of said cross-bars and adapted when moved to cause a lateral shifting of the

plow-supporting frame relative to the wheel-frame.

19. In a plow, the combination with a wheel-frame comprising side bars and two cross-bars extending between said side-bars, of a plow-supporting frame of materially less width than the wheel-frame and comprising two horizontal side members and an upright arch, said arch having two principal parts connected together and to the said horizontal side members and arranged upon opposite sides of the said cross-bars of the wheel-frame, a rolling support secured between the two arch members and bearing upon one of the cross-bars of the frame, a rack on the other of said cross-bars, a gear journaled in the said arch and meshing with said rack, and means for rotating said gear.

20. In a plow, the combination with a frame comprising side bars and a cross-bar extending between them, of a plow-body, a plow-body supporting frame having an arch member extending up and adjacent to the said cross-bar of the wheel-frame, a rack on said cross-bar, a gear journaled in said arch member and in mesh with said rack, a shaft fast to said gear, a bracket in which said shaft is journaled, a crank handle connected to the shaft, and a device secured to said bracket for locking said handle in any position to which it may be turned.

21. In a plow, the combination with a frame comprising side bars and a cross-bar extending between them, of a plow-body, a plow-body supporting frame having an arch member extending up and adjacent to the said cross-bar of the wheel-frame, a rack on said cross-bar, a gear journaled in said arch member and in mesh with said rack, a shaft fast to said gear, a bracket in which said shaft is journaled, a crank handle connected to the shaft, and a notched plate secured to said bracket, any one of the notches of which are adapted to be engaged by the handle for locking said handle, shaft and gear against rotation.

22. In a plow, a wheel-frame comprising a vertical wheel standard at each side of the machine, a vertical bar adjacent to each wheel-standard with which bars said standards are respectively slidingly connected, and means connecting said bars together, in combination with a plow-supporting frame connected with the wheel-frame and laterally adjustable relative thereto, and means for automatically raising one side of the wheel-frame and lowering the other when the plow-supporting frame is shifted laterally.

23. In a plow, a wheel-frame comprising a vertical wheel standard at each side of the machine, a vertical bar adjacent to each wheel-standard with which bars said standards are respectively slidingly connected,

and means connecting said bars together, in combination with a plow-supporting frame attached to and movable along said means that connect the wheel-frame bars together, and means for automatically raising one side of the wheel-frame and lowering the other when the plow-supporting frame is shifted laterally.

24. In a plow, the combination with a wheel-frame comprising wheel standards that are relatively vertically adjustable, of a plow-supporting frame connected with and laterally adjustable of the wheel-frame, a movable member connecting said wheel standards together, and means for automatically moving said member to cause relative movements in opposite directions of the wheel standards when the plow-supporting frame is adjusted laterally of the wheel-frame.

25. In a plow, the combination with a wheel-frame comprising wheel standards that are relatively vertically adjustable, of a plow-supporting frame connected with and laterally adjustable of the wheel-frame, a pair of members each connected with each of said wheel-standards at opposite sides of said standards, and means for automatically moving said members to cause relative movements in opposite directions of the wheel-standards when the plow-supporting frame is adjusted laterally of the wheel-frame.

26. In a plow, the combination with a wheel-frame comprising wheel standards that are relatively vertically adjustable, of a plow-supporting frame connected with and laterally adjustable of the wheel-frame, a rocking cross-bar connecting said wheel standards together, and means for automatically moving said rocking cross-bar to cause relative movements in opposite directions of the wheel standards when the plow-supporting frame is adjusted laterally of the wheel-frame.

27. In a plow, the combination with a wheel-frame comprising wheel standards that are relatively vertically adjustable, of a plow-supporting frame connected with and laterally adjustable of the wheel-frame, a rocking cross-bar connecting said wheel standards together, means for automatically moving said rocking cross-bar to cause relative movements in opposite directions of the wheel standards when the plow-supporting frame is adjusted laterally of the wheel-frame, and means for adjusting said rocking cross-bar to a position where it will not be affected by the movements of the plow-supporting frame.

28. In a plow, the combination with a wheel-frame comprising wheel-standards that are relatively vertically adjustable, of a plow-supporting frame connected with and laterally adjustable of the wheel-frame, and

means operated by the lateral adjustment of the plow-supporting frame for causing the lowering of one side of the wheel-frame and the raising of the other side of the wheel-frame.

29. In a plow, the combination with a wheel-frame comprising wheel-standards that are relatively vertically adjustable, of a plow-supporting frame connected with and laterally adjustable of the wheel-frame, and means operated by the lateral adjustment of the plow-supporting frame for causing simultaneous lowering of one side of the wheel-frame and a corresponding raising of the other side.

30. In a plow, a wheel-frame comprising relatively-adjustable vertical wheel-standards, vertical side-bars slidingly connected with said standards, and means connecting said bars, of a laterally-adjustable plow-supporting frame having an upwardly-extending member movably connected with the said means that connect the side bars, a rocking cross-bar connecting the wheel-standards, and means carried by the upwardly-extending member of the plow-supporting frame for causing at each lateral movement of the plow-supporting frame a rocking of said cross-bar to simultaneously move opposite sides of said wheel-frame in different directions.

31. In a plow, a wheel-frame comprising relatively-adjustable vertical wheel-standards, vertical side-bars slidingly connected with said standards, and means connecting said bars, of a laterally-adjustable plow-supporting frame having an upwardly-extending member movably connected with the said means that connect the side bars, a rocking cross-bar connecting the wheel-standards, a pair of levers pivotally connected together and each pivoted to the said cross-bar at opposite sides of the central part of said bar, means for holding said levers at an angle to said cross-bar, and two contact devices carried by the upwardly-extending member of the plow-supporting frame, each of which is adapted to contact with one of said levers to cause a movement of the cross-bar at each transverse shifting of the plow-supporting frame.

32. In a plow, a wheel-frame comprising relatively-adjustable vertical wheel-standards, vertical side-bars slidingly connected with said standards, and means connecting said bars, of a laterally-adjustable plow-sup-

porting frame having an upwardly-extending member movably connected with the said means that connect the side bars, a rocking cross-bar connecting the wheel-standards, a 60 pair of levers pivotally connected together and each pivoted to the said cross-bar at opposite sides of the central part of said cross-bar, means for adjusting said levers to different inclinations with respect to said cross-bar or in substantial alinement with said cross-bar, and two devices carried by the upwardly-extending member of the plow-supporting frame, each of which is adapted to contact with and move one of said levers, 70 when said levers are in an inclined position, to cause a movement of the cross-bar at each transverse shifting of the plow-supporting frame.

33. In a plow, a wheel-frame comprising 75 a vertical wheel-standard at each side of the machine and means connecting said standards, said means being vertically adjustable with relation to the standards, in combination with a plow-body, means for connecting 80 the same to the wheel-frame, a movable cross-bar connected to said two standards, and means for forcing the ends of said cross-bar in opposite directions to impart corresponding relative movements to the standards.

34. In a plow, the combination of a supporting wheel at each side of the machine, a vertical standard connected with each wheel, a vertical bar slidingly connected to each standard, means connecting said vertical bars together, a movable cross-bar connected between its ends with said bar-connecting means and connected at each of its ends with one of said wheel-standards, and means for 95 moving said cross-bar to impart simultaneous vertical movements in opposite directions to said bars.

35. In a plow, the combination of a supporting wheel at each side of the machine, a 100 vertical standard connected with each wheel, a vertical bar slidingly connected to each standard, means connecting said vertical bars together, a pair of parallel cross-bars located at opposite sides of said bar-connecting means and connected therewith and having their end portions connected respectively with said wheel-standards, and means for moving said cross-bars to impart simultaneous vertical movements in opposite directions to said bars.

ANDREW SHEARER.
